ORIFICE FITTING DEVICE

John W. Whalen, Inglewood, Calif., assignor to
 Daniel Orifice Fitting Company, Los Angeles,
 Calif., a corporation of California

Application July 30, 1951, Serial No. 239,367

7 Claims. (Cl. 138—44)

1

This invention relates to orifice meter valve devices of the general type shown in the Daniel Patents 1,965,826 of July 10, 1944 and 1,996,192 of April 2, 1935. Devices of this type are commonly employed in connection with pipe lines for measuring the flow of fluids, steam, gases, air and vapors through the line. Such devices employ an orifice plate which is removable from operative position for purposes of inspection, maintenance or substitution. These devices make it possible to change orifice plates under pressure without interruption of flow of fluid through the pipe line and without requiring bypass valves as used in conventional orifice flange installations.

It is the object of the present invention to provide an improved form of orifice plate valve assembly of this type which is particularly adapted for, but not limited to, installations of relatively large size.

Another object is to provide a device of this type which is rugged and reliable in design and operation and which enables the orifice plate and carrier to be moved to and from operative position with a minimum of effort in order to encourage frequent inspection.

A more detailed object is to provide improved means for withdrawing the orifice plate carrier from operative position.

Another object is to provide an externally accessible adjustable brake mechanism so that the rate of travel of the plate carrier may be carefully controlled, and avoiding any impact blows and possible damage to valve member separating lower and upper chambers of the orifice device.

Other and more detailed objects and advantages will appear hereinafter.

In the drawings:

Figure 1 is a front elevation partly broken away and partly in section showing a preferred embodiment of my invention.

Figure 2 is a transverse sectional view taken substantially on the line 2—2 as shown in Figure 1.

Figure 3 is a side elevation partly broken away taken in the direction 3—3 as shown in Figure 1.

Figure 4 is a transverse sectional view partly broken away taken substantially on the line 4—4 as shown in Figure 1.

Figure 5 is a fragmentary sectional view similar to a portion of Figure 4 and showing the plate carrier stop in operative position.

Figure 6 is a fragmental sectional plan view

2

taken substantially on the line 6—6 as shown in Figure 1.

Figure 7 is a sectional view showing a portion of Figure 1 on an enlarged scale and showing details of one of the stuffing box assemblies.

Figure 8 is a fragmentary end elevation taken in the direction 8—8 as shown in Figure 1.

Figure 9 is a side elevation partly in section showing details of a wrench employed in connection with the device embodying my invention.

Figure 10 is a front elevation of the wrench.

Figure 11 is a fragmentary sectional view similar to a portion of Figure 4 but showing the horizontal slide valve in closed position.

Referring to the drawings, the stationary body 10 is provided with integrally formed support feet 11^a and is formed with a central axial bore 12. The ends of the body may be provided with the usual flanges if desired for connection to aligned pipes (not shown), or the body may be provided with lips 13 for connection to such pipes by welding. The chamber housing 14 is connected to the body 10 by means of threaded fastenings 15, and a pair of plate carrier guide brackets 16 are secured to the upper end of the chamber housing by means of suitable threaded fastenings 17. The housing 14 may be provided with stiffening flanges or ribs 9 of any suitable or desirable configuration.

A plate carrier 18 is adapted to be received within a transverse slot 19 provided in the body 10, and an orifice plate 20 having a central opening 20^a is mounted on the carrier 18. The carrier 18 is provided with rack teeth 21 along parallel vertical edges, and these rack teeth are engaged by spur pinions 22 fixed on the shaft 23. Similar spur pinions 24 and 25 are fixed on shafts 23 and 27^a respectively. Shaft 26 extends through the chamber 27 within the housing 14, while shaft 27^a extends between the brackets 16. The shafts 23, 26 and 27^a may be turned in sequence, as described more fully hereinafter, to raise the plate carrier 18 and its orifice plate 20 from the operative position shown in Figure 2 upwardly through the chamber 27 and into the inspection position shown in Figure 5.

As shown clearly in Figure 4, the body 10 is provided with walls forming a cavity 11 which communicates with the slot 19. The spur pinions 22 on the shaft 23 are positioned within this cavity. The horizontally slidable valve member 28 is also mounted within this cavity 11 and is arranged to slide horizontally on rails 29 fixed

at each end of the cavity. The rails 29 are held in position by suitable threaded attachment fittings 29^a (see Figure 7). A stationary valve seat member 30 is positioned within the cavity 11 and has a sealing face 31 on its lower surface. This stationary seat member 30 is fixed to the housing 14 by means of suitable threaded fastener elements 32. A gasket 33 prevents leakage between the seat 30 and the housing 14. A movable valve 34 is guided for vertical sliding movement on the valve member 28 and a plurality of springs 35 are provided for moving the valve 34 upwardly into contact with the lower surface of sealing face 31. Parallel horizontal racks 36 are provided on the valve member 28, and these racks mesh with gears 37 fixed on the valve shaft 38. A limit stop 39 is fixed on the stationary valve seat 30, and this stop is engaged by the valve member 28 when it is moved to the left from the position shown in Figure 4.

During the normal operation of the device, that is, when the carrier 18 and orifice plate 20 are in the position shown in Figure 2, the valve member 28 is normally in contact with the stop 39, and in this position the moving valve 34 blocks off the central passage 40 in the stationary seat 30. The line pressure normally existing within the cavity 11 supplements the action of the springs 35 in maintaining the valve 34 in tight sealing relationship with the surface 31.

Means are provided for injecting lubricant such as grease between the seat 30 and valve 34, and as shown in the drawings this means includes a pressure applying fitting 41 threaded to the housing 14 and communicating with a lubricant passage 42. The lubricant passage 42 extends through the gasket 33 and through the seat 30 and communicates with a groove 43 which encompasses the central opening 40 in the seat 30. The lubricant applied under pressure prevents the seat 30 and valve 34 from sticking and enables the moving valve 34 to be shifted laterally to the open position shown in Figure 4 without undue friction.

The body 10 is sealed with respect to the housing 14 by means of a continuous non-metallic sealing ring 44 which is mounted within a continuous groove 45 provided in the lower face of the housing 14. Means are provided for equalizing the pressure within the chamber 27 and cavity 11, and as shown in the drawings this means includes a pressure equalizing valve assembly 46. A passageway 47 leads from the cavity 11 to the valve assembly 46, and another passageway 48 leads from the valve assembly 46 to the chamber 27. The valve assembly 46 includes a packing nut 49 which is externally threaded for mounting on the housing 14. The stem 50 extends through the packing nut 49, and the inner end of the stem engages the ball 51 to hold it against the seat 52, thereby preventing flow through the passageway 47. Packing 53 is positioned to be compressed by the packing nut 49 to form a seal about the stem 50. When the stem 50 is turned by means of a wrench (not shown) the ball 51 is moved away from the seat 52 by pressure in the passageway 47. This pressure is communicated through passageway 48 to the chamber 27.

The upper end of the chamber 27 is normally sealed by means of a closure plate 54 having a continuous seal ring 55. The closure 54 is normally held in sealing position by means of two rows of set screws 56 which are threaded into the clamping plate 57. The clamping plate 57 is insertable endwise into the groove 58 formed in

the upper portion of the housing 14, and when in place the clamping plate is engaged by the lateral shoulders 59 on the housing 14. Two rows of set screws 56 are employed instead of a single row in order to reduce bending stresses in the plate 57 and closure 54 and to apply compressive forces more nearly in a position directly over the continuous seal element 55. When the horizontal sliding valve is to be opened the stem 50 of the equalizer valve 46 is first turned so that pressure reaches the chamber 27 by way of the passageways 47 and 48. With the pressure thus balanced across the valve plate 34, the valve member 28 may be moved to the open position shown in Figure 4 with a minimum of frictional resistance. The pressure is held by the sealing element 55.

The valve actuating shaft 38 extends through opposed ends of the body 10 and is provided with squared ends for reception of a wrench. As shown in Figure 8 an indicator plate 60 is fixed to each of the exposed ends of the shaft 38. This plate acts in conjunction with a stationary indicator 61 to provide a visual indication of the internal position of the sliding valve member 28.

Figure 7 shows a typical stuffing box assembly which is employed for each end of each of the shafts 23, 33 and 28 at the point where they pass through the body 10 or housing 14. As shown in Figure 7, the shaft 23 passes through an inner stuffing box assembly generally designated 62 and an outer stuffing box assembly 63. Both assemblies are carried on a sleeve 64 which extends into an opening 65 provided in the body 10. Threads 66 connect the sleeve to the body 10. A bushing 67 has a peripheral groove 68 which is engaged by a set screw 69 carried on the sleeve 64. A spring 70 encircling the shaft 23 bears against the bushing 67 at one end and against a metal washer and a series of packing rings 71 at the other end. The outer packing assembly 63 includes a metal washer and packing rings 72 which are compressed by a gland 73 and a follower nut 74. The inner packing assembly 62 is capable of minimizing leakage outwardly along the shaft 23 so that the outer packing 72 may be replaced when necessary without shutting down the unit.

The shafts 26 and 75 are rotatably mounted in end flanges 76 and 77 fixed to the chamber housing 14. Threaded attachment fittings 78 are provided for securing the flanges 76 and 77 in position. Stuffing box assemblies 79 of the general type shown in Figure 7 are provided for opposed ends of the shaft 26 to prevent leakage at the point where the shaft extends through the flanges 76 and 77. The roller shaft 75 does not extend through the flanges 76 and 77, but on the contrary is rotatably supported within such flanges. Rollers 80 are mounted on the shaft 75 for contacting the face of the carrier 18 on the side opposite the rack teeth 21.

The roller shafts 81 and 82 are rotatably mounted on the blind flanges 83 and 84. These flanges are fixed to the chamber housing 14 by means of threaded attachment fittings 85. Figure 6 shows the manner of rotatably supporting the roller shafts 81 and 82 within the end flange 84. Parallel bores 86 are provided with bearing sleeves 87 which rotatably support the shafts 81 and 82. The shaft rollers 88 and 89 are each provided with a set screw 90 which engages within a groove 91 provided in the roller shaft. The bearing supports for the ends of the shaft 75 are

substantially identical to that shown in Figure 6 for shafts 81 and 82.

Since the housing 14 is ordinarily formed as a relatively large size casting the chamber 27 may have walls which are not disposed in precisely parallel planes, but on the contrary may be slightly warped or distorted. The position of the shafts 26, 75, 81 and 82 are therefore made subject to shifting with respect to the housing 14. This is accomplished by providing clearance between the openings 92 in the end flanges 76, 77, 83 and 84 and the threaded fastening elements which secure the end flanges to the housing 14. At the time the shafts 26, 75, 81 and 82 are initially assembled at the factory they are shifted to the proper position so that they are effective to raise and lower the plate carrier 18 through the chamber 27 without dragging on the walls thereof. The end flanges are then fixed to the housing 14 by means of pairs of dowel pins 93 (see Figure 3).

When the plate carrier 18 is to be raised from the chamber 27 for inspection, maintenance, or replacement of the orifice plate 20, the valve member 28 is moved back to its sealing position, equalizer valve 46 closed, and the bleeder valve 94 is opened to bleed down the pressure within the chamber 27. The screws 56 are turned in a direction to release the pressure against the closure 54 so that it may be removed in an axial direction. The clamp plate 57 is likewise removed axially, and this clears the path for raising the plate carrier 18. The spur pinions 24 engage the rack 21 so that turning of the shaft 26 moves the plate carrier 18 upwardly between the rollers 88 and 89 on the roller shafts 81 and 82. The rack 21 engages the teeth of the spur pinions 25 so that when the shaft 27^a is turned the plate carrier 18 is raised to the position shown in Figure 5. The rollers 95 on the roller shaft 96 engage the backside of the plate carrier 18 to maintain the spur pinions 25 in mesh with the rack 21. When the lower end of the plate carrier 18 is raised above the surface 97 at the upper end of the housing 14 the plate carrier stop 98 is swung to a position shown in Figure 5 so that the plate carrier 18 is prevented from dropping back into the chamber 27. The plate carrier stop is connected to the housing 14 by means of a bushed pivot bolt 99. Guide ribs 100 form a channel for reception of the plate carrier 18 so that the latter is held in an upright position while the orifice plate 20 is inspected, installed or removed.

A brake device generally designated 101 may be provided for frictionally restraining the speed of rotation of the shaft 26 to limit the downward speed of travel of the plate carrier 18 when it is being reinserted into the chamber 27 and into the slot 19. As shown in Figures 1 and 3 of the drawings, this brake device 101 includes a nonrotary bracket 102 having an ear 103 fixed in position by means of the anchor bolt 104. The bracket 102 is provided with a split sleeve 105 which has a cylindrical bore which is provided with split friction bushing 106 to receive a portion of the shaft 26. A cap screw 107 is provided to clamp the halves of the split sleeve 105 into frictional engagement with the shaft 26. When the cap screw 107 is tightened the frictional resistance on the shaft is increased. The operator may tighten the cap screw 107 to a sufficient extent to prevent rotation of the shaft 26 when the weight of the plate carrier 18 is applied to the spur pinion 24 through the rack 21. The operator may then apply a

wrench to either of the squared ends of the shaft 26 to lower the plate carrier at the desired rate, thereby avoiding any impact blows and possible damage to parts in the event the relatively heavy plate carrier 18 and orifice plate 20 should drop by gravity.

For convenience I provide a special wrench 120 shown in Figures 9 and 10 which is provided with a first socket 121 for engaging the squared ends 10 of the shafts 23, 38, 26 and 27^a and a second socket 122 for reception of the heads of the cap screws 56. The handle 123 of the wrench has an axis which is parallel to the axis of the socket 121. The axis of the socket 122 is disposed at an angle 15 to the axis of the first socket 121 in order that the socket 122 may be applied to the heads of the cap screws 56 without interference between any part of the wrench and the structure of the orifice fitting valve device. When the socket 122 is 20 used for releasing the set screws 56 the boss 124 is used as a handle by the operator.

In operation of the device the plate carrier 18 and orifice plate 20 are normally in position within the slot 19 as shown in Figure 2. In this position the plate carrier rests on up-ended studs 125 which are welded in position. Vulcanized resilient sealing lips 126 are provided on the orifice plate 20, and these seal against the annular sealing surfaces 127 provided on opposite sides of the slot 19. The meter flange taps 128 are provided on opposite sides of the slot 19 and on both sides of the orifice device for connection to pressure differential indicating manometers, gauges, or recording charts (not shown). When it is desired 30 to remove the orifice plate 20 for inspection, maintenance or replacement the equalizing valve 46 is first actuated to pressurize the chamber 27. The bleed valve 94 remains closed. When the pressure is equalized between the cavity 11 and the chamber 27 the valve member 28 is moved to open position by applying the wrench 120 to the squared end of the valve operating shaft 38. Turning of the shaft 38 turns the gear 37 and moves the meshing rack 36 on member 28 to the right as viewed in Figure 4. The wrench 120 is 35 then applied to the squared end of shaft 23. Turning of the shaft 23 causes the spur pinion 22 which meshes with the rack 21 to raise the plate carrier 18 and orifice plate 20 vertically through the cavity 11 and into the chamber 27. The brake 101 is adjusted to apply frictional resistance to the shaft 26. When the plate carrier 18 has been raised sufficiently to bring the rack teeth 21 into engagement with the teeth on the spur pinion 24 the wrench 120 is transferred to the squared end of the shaft 26. The plate carrier 18 and orifice plate 20 do not fall by gravity 40 during the time interval while the wrench is being transferred because the brake 101 frictionally prevents rotation of the shaft 26.

When the plate carrier 18 and orifice plate 20 are positioned wholly within the chamber 27 the shaft 38 is turned to close the horizontal sliding valve member 28. The equalizer valve 46 is then 45 closed. Pressure within the chamber 27 is bled off by opening valve 94. The closure 54 and clamp plate 57 are removed after the cap screws 56 have been released so that the last barrier is removed to permit upward movement of the plate carrier 18 and orifice plate 20 for visual inspection. The shaft 26 is turned in a direction to raise the plate carrier 18 until the rack teeth 21 mesh with the spur pinion 25 on the shaft 27^a. The wrench 120 is then transferred to the shaft 27^a while the 50 brake 101 prevents retrograde motion of the plate

carrier 18. The shaft 27^a is then turned to bring the plate carrier and orifice plate into view between the guide ribs 109 on the brackets 16. The plate carrier stop 98 is swung beneath the lower end of the plate carrier 18, thereby supporting it in raised position.

The particular mounting of the orifice plate 20 on the plate carrier 18 forms no part of the present invention, and any suitable or desirable form of mounting may be employed.

The bleed valve 94 is then closed, and after the orifice plate 20 has been inspected or replaced, the carrier 18 and orifice plate 20 are returned through the chamber 27 and cavity 11 into operative position within the slot 19. This is accomplished in several steps taken in the reverse order as described above. An abutment 129 (see Figure 4) is provided on the horizontally movable valve member 28, and the purpose of this abutment is to engage the plate carrier 18 in the event that it has not dropped to its operative position as shown in Figure 2. When the plate carrier 18 rests properly on the supporting studs 125 the abutment 129 clears the upper end of the plate carrier 18 so that the valve member 28 may be moved horizontally to sealing position.

Having fully described my invention, it is to be understood that I do not wish to be limited to the details herein set forth, but my invention is of the full scope of the appended claims.

I claim:

1. In an orifice fitting device of the class described, the combination of: a body having a flow passage extending therethrough, the body also having a transverse slot and a cavity, a plate carrier, an orifice plate mounted on the carrier and having a central opening for alignment with said flow passage, the carrier having rack teeth, gear means within the cavity engageable with the rack teeth, a housing fixed to the body and having a central chamber, a shaft rotatably mounted on the housing and extending into the chamber, a gear on the shaft within the chamber adapted to mesh with the rack on the plate carrier, laterally shiftable valve means within the body cavity for sealing one end of said chamber, removable means forming a seal at the other end of said chamber, spaced brackets on the housing exteriorly of said chamber for guiding the plate carrier, gear means supported on the brackets and adapted to mesh with the rack on the plate carrier, the plate carrier being movable from operative position within the slot through the cavity and chamber to an inoperative position between said brackets, and brake means outside the chamber operatively associated with said shaft for frictionally retarding rotation of the shaft.

2. In an orifice fitting device of the class described, the combination of: a body having a flow passage extending therethrough, a plate carrier removably mounted within the body, an orifice plate on the carrier having a central opening aligned with said body passage, a housing fixed to said body and having a chamber, laterally shiftable valve means forming a seal between one end of the chamber and the interior of said body, removable means at the other end of the chamber forming a seal, a pair of spaced guide members fixed to the housing adjacent said removable means, the said members having grooves to receive side edges of the plate carrier, and means for moving the plate carrier and orifice plate from operative position within the body

through the chamber and into position between said spaced guide members.

3. In an orifice fitting device of the class described, the combination of: a body having a flow passage extending therethrough, a plate carrier removably mounted within the body, an orifice plate on the carrier having a central opening aligned with said body passage, a housing fixed to said body and having a chamber, laterally shiftable valve means forming a seal between the lower end of the chamber and the interior of said body, removable means at the other end of the chamber forming a seal, a pair of spaced brackets fixed to the housing adjacent said removable means, the brackets having grooves to receive side edges of the plate carrier, means for raising the plate carrier and orifice plate from operative position within the body through the chamber and into position between said spaced brackets, and a stop element movably mounted on the housing for maintaining the plate carrier in raised position.

4. In an orifice fitting device of the class described, the combination of: a body having a flow passage extending therethrough, a plate carrier removably mounted within the body, an orifice plate on the carrier having a central opening aligned with said body passage, a housing fixed to said body and having a chamber, laterally shiftable valve means forming a seal between one end of the chamber and the interior of said body, removable means at the other end of the chamber forming a seal, a pair of spaced guide members fixed to the housing adjacent said removable means, the guide members having grooves to receive side edges of the plate carrier, and means for moving the plate carrier and orifice plate from operative position within the body through the chamber and into position between said spaced guide members, said means including a rack on the plate carrier and a series of spaced pinion gears for sequentially meshing with said rack.

5. In an orifice fitting device of the class described, the combination of: a body having a flow passage extending therethrough, a plate carrier removably mounted within the body, an orifice plate on the carrier having a central opening aligned with said body passage, a housing fixed to said body and having a chamber, laterally shiftable valve means forming a seal between one end of the chamber and the interior of said body, removable means at the other end of the chamber forming a seal, a pair of spaced guide members fixed to the housing adjacent said removable means, the guide members having grooves to receive side edges of the plate carrier, and means for moving the plate carrier and orifice plate from operative position within the body through the chamber and into position between said spaced guide members, said means including a rack on the plate carrier and a series of spaced pinion gears for sequentially meshing with said rack, and a stop element for maintaining the plate carrier in the latter said position.

6. In an orifice fitting device of the class described, the combination of: a body having a flow passage extending therethrough, a plate carrier removably mounted within the body, an orifice plate on the carrier having a central opening aligned with said body passage, a housing fixed to said body and having a chamber, laterally shiftable valve means forming a seal between one end of the chamber and the interior of said body,

removable means at the other end of the chamber forming a seal, a pair of spaced guide members fixed to the housing adjacent said removable means, the guide members having grooves to receive side edges of the plate carrier, and means for moving the plate carrier and orifice plate from operative position within the body through the chamber and into position between said spaced guide members, said means including a rack on the plate carrier and a series of spaced pinion gears for sequentially meshing with said rack, said means also including a plurality of rollers on the housing for guiding the plate carrier through the housing and for maintaining the rack in mesh with the pinion gears.

7. In an orifice fitting device of the class described, the combination of: a body having a flow passage extending therethrough, a plate carrier removably mounted within the body, an orifice plate on the carrier having a central opening aligned with said body passage, a housing fixed to said body and having a chamber, laterally shiftable valve means forming a seal between one end of the chamber and the interior of said body, removable means at the other end of the chamber

20
25

forming a seal, a pair of spaced guide members fixed to the housing adjacent said removable means, the guide members having grooves to receive side edges of the plate carrier, and means for moving the plate carrier and orifice plate from operative position within the body through the chamber and into position between said spaced guide members, said means including a rack on the plate carrier and a series of spaced pinion gears for sequentially meshing with said rack, said means also including a plurality of rollers on the housing for guiding the plate carrier through the housing and for maintaining the rack in mesh with the pinion gears, and a stop element for maintaining the plate carrier in the latter said position.
